By his atty.

UNITED STATES PATENT OFFICE.

JOHN H. PALMER, OF ROCKAWAY, NEW JERSEY.

CAR-STARTER.

SPECIFICATION forming part of Letters Patent No. 398,438, dated February 26, 1889.

Application filed May 7, 1888. Serial No. 273,064. (No model.).

To all whom it may concern:

Be it known that I, JOHN H. PALMER, of Rockaway, county of Morris, State of New Jersey, have invented an Improvement in Car-starters, of which the following is a specification.

My invention has reference to car-starters; and it consists of certain improvements, all of which are fully set forth in the following specification, and shown in the accompanying drawings, which form a part thereof.

The object of my invention is to provide a suitable construction of car-starter which shall be simple and durable in operation and easily manipulated.

In carrying out my invention I connect the car-starter to the car-body and preferably to the under part of the front platform, and couple it with the axle or axles of the car by chains and sprocket-wheels, or otherwise.

The starter itself consists, essentially, of a friction-clutch between the starter-shaft and a loose wheel having a spirally-arranged rope or chain groove, and over which the rope or chain passes to connect said grooved wheel with the draw-bar to which the horses are attached. This draw-bar is normally locked against being drawn out after the car is started, but at starting the lock is removed, so that the rope or chain is drawn out, rotating the grooved wheel with a preferably gradually-increasing velocity, and this, through the mediation of the friction-clutch, causes the car to be put into motion. After the car is started the clutch is automatically loosened, and a spring device returns the parts to their normal positions when the draw-bar is locked, as before.

The principle on which the apparatus operates is that the horses travel a greater distance than the car in starting it from a state of rest over given space; and, furthermore, with a steady and uniform pull on the draw-bar the car is caused to move with a gradually-accelerated motion, whereby the final action of the draw-bar brings the car to its proper speed.

Another feature of my improvements is that while the horses start off with a pull of great leverage, starting the car from state of rest easily, their final pull on the draw-bar and

rope or chain is as if the pull were directly upon the car-body, and hence all of the changes are gradual and there are no sudden strains upon the horses.

In the drawings, Figure 1 is a sectional side elevation of the forward end of a car with my improvement applied thereto. Fig. 2 is a front elevation of the car-starter removed. Fig. 3 is a sectional elevation of same on line *x*-*x*. Fig. 4 is a sectional elevation of same on line *y*-*y*. Fig. 5 is a cross-sectional elevation of Fig. 4 on line *z*-*z*, and Fig. 6 is a sectional side elevation of a car with a modification of my invention applied thereto.

55

A is the car-body.

B is the car-starter proper, and is connected thereto at any convenient place, preferably under the front platform, as shown. Motion is communicated from the starter to the axles *E* by means of the sprocket-wheels *C* and *d*, and chain *D*, or by gearing or other suitable well-known power-transmitting devices.

Referring now to the car-starter *per se*, *F* is the draw-bar, to which the horses are attached in any convenient manner. This draw-bar *F* is connected to a wire rope or chain, *f*, and first passes under the guide-pulley *R* on the axis *r*, and then to the wheel *J*, passing around its groove *j* and being secured at its distant end. This groove *j* is preferably like a spiral, so that as the rope is pulled and the wheel *J* rotates the leverage becomes less and less until it equals the pitch of the sprocket-wheel *C* on the starter-shaft *K*, and as the sprocket-wheels *C* and *d* are preferably of unequal diameters the final pull by the horses equals the pull upon the car direct. By this means the horses start off at a given pull which is substantially equal to that of the car in full motion, and as the car has its speed increased the leverage decreases, so that the pull of the horses remains the same.

G is a lock to hold the draw-bar in when the starter is not being used. This lock consists of a pivoted lever fulcrumed on *r*, and having a slotted end at *g*, which fits down around the draw-bar and prevents its being pulled out.

H is a foot-lever which acts upon a rear extension of the lever *G* and causes it to be oscillated to unlock the draw-bar when desired.

to start the car. Normally, or when the car is in motion, the locks holds the draw-bar in.

The shaft K is loosely journaled in the bearings *i* in the frame I of the starter, to which all of the parts are directly or indirectly attached. Secured to the shaft K is the friction band-wheel L, and upon its hub or shaft is loosely journaled the grooved wheel J.

M is a steel friction-band and connects at its ends with two transverse pins or rods, O and P, secured to a U-shaped frame, N, pivoted to the wheel J, and an extension thereof at *n*, or between the rods O and P and the central shaft, K. The extension of the wheel J is J', and is secured to it by the connecting-bars J''. This frame N is free to oscillate on *n* as a fulcrum, and in doing so its movement in one direction makes the band M bind upon the band-wheel, and in the other direction causes the band to become loose upon the band-wheel. The rod P is made to extend from both ends through slots *c* in the wheel J and extension J', and are connected to the ends of springs *p*, encircling the bearings *i* and having their other ends connected with the frame I, as shown in Fig. 2.

It is evident that if the wheel J is moved in the direction of the arrow the springs *p* will pull upon the rods P in the opposite direction and cause the frame N to rotate on P as a fulcrum and tighten the band upon the band-wheel L. As the wheel J is moved around, the band-wheel, its shaft K, and sprocket-wheel C are rotated, also giving the main axle and its wheels substantially one revolution and the car a movement forward of about seven feet. When the full rotation of the wheel J has been made, the extended end U of the frame N strikes a lug, S, on the frame I or one of its bearings, and this oscillates it against the action of the springs *i* and releases the band M from wheel L, which continues to rotate, and the momentum of the car carries it forward, and the slackening on the rope or chain *f* allows the springs *i* to return the wheel J and connections to their normal or original position, and in so returning the effect of the spring and also the movement of wheel L is to keep the band M loose. When the parts return to their original position, the frame N at its end may rest against the frame I at T, Fig. 4, and the lock G is dropped to hold the draw-bar from being pulled out upon further action of the horses while the car is in motion. It will be noticed that in the mechanical action of this starter the two rods O and P are alternately acting as fulcrums, according as to whether the band is to be released from the wheel L or tightened upon it.

I do not confine myself to the details of construction, as the parts may be modified in various ways without departing from the spirit of my invention. For instance, one modification of this apparatus is shown in Fig. 6, in which the same letters correspond to similar parts in the other figures already

described. In this case the grooved wheel J has a groove of the same radius, and G' is the lock for the wheel J in place of acting on the draw-bar. This lock G' is moved into or out of place by a link, H², which in turn may be locked down by a pivoted foot-lock, H', to prevent the lock G' from moving out of the way of the wheel J. In this case the rope *f* has its end connected with the piece N, and the spring *p* in this case would be connected to the inner rod, P, while the outer rod, O, would be pivoted to the wheel J. When the rope *f* pulls the wheel J around, it operates the lever-piece N and makes the band M grip the wheel L to propel the car. When the rope *f* is released the spring would pull upon the rod P and release the band M.

The mere details of construction may be modified in various ways without changing the principles of the invention, and hence I do not limit myself thereto.

Having now described my invention, what I claim as new, and desire to secure by Letters Patent, is—

1. In a car-starter, the combination of an extensible draw-bar, a wheel operated thereby, a friction-clutch wheel, and a friction-clutch band encircling said friction-clutch wheel, a band-tightening connection between the band and wheel operated by the draw-bar, and a power-connection for connecting the friction-clutch wheel and axle of the vehicle.

2. In a car-starter, the combination of an extensible draw-bar, a wheel operated thereby, a friction-clutch wheel, a friction-clutch band encircling said friction-clutch wheel, a band-tightening connection between the band and wheel operated by the draw-bar, a power-connection for connecting the friction-clutch wheel and axle of the vehicle, and a spring to return the draw-bar and its wheel to their normal position after the vehicle has started.

3. In a car-starter, the combination of an extensible draw-bar, a lock to prevent said draw-bar being drawn out except when desired, a wheel operated thereby, a friction-clutch wheel, and a friction-clutch band encircling said friction-clutch wheel, a band-tightening connection between the band and wheel operated by the draw-bar, and a power-connection between the friction-clutch wheel and axle of the vehicle.

4. In a car-starter, the combination of an extensible draw-bar, a lock to prevent said draw-bar being drawn out except when desired, a wheel operated thereby, a friction-clutch wheel, and a friction-clutch band encircling said friction-clutch wheel, a band-tightening connection between the band and wheel operated by the draw-bar, a power-connection for connecting the friction-clutch wheel and axle of the vehicle, and a spring acting upon the band-tightening connection to make it unclutch the band-wheel and return the draw-bar and its wheel to their original and normal position.

5. The combination, in a car-starter, of a

- power-shaft having a friction-wheel secured thereto, a loose wheel supported concentric with said shaft, a draw-bar, a connection between said draw-bar and loose wheel, a lock 5 to hold said draw-bar from being pulled out except when desired, a friction-band encircling the friction-wheel, and a band-tightening device carried by the loose wheel.
6. The combination, in a car-starter, of a power-shaft having a friction-wheel secured thereto, a loose wheel supported concentric with said shaft and having a spirally-formed rope or chain surface, a draw-bar, a flexible 10 connection between said draw-bar and loose wheel, a lock to hold said draw-bar from being pulled out except when desired, a friction-band encircling the friction-wheel, and a band-tightening device carried by the loose wheel.
- 15 7. The combination, in a car-starter, of a power-shaft having a friction-wheel secured thereto, a loose wheel supported concentric with said shaft, a draw-bar, a connection between said draw-bar and loose wheel, a lock 20 to hold said draw-bar from being pulled out except when desired, a friction-band encircling the friction-wheel, a band-tightening device carried by the loose wheel, and a spring to return the draw-bar and loose wheel 25 to their normal position after being put in motion.
8. The combination, in a car-starter, of a power-shaft having a friction-wheel secured thereto, a loose wheel supported concentric with said shaft and having a spirally-formed rope or chain surface, a draw-bar, a flexible 30 connection between said draw-bar and loose wheel, a lock to hold said draw-bar from being pulled out except when desired, a friction-band encircling the friction-wheel, a band-tightening device carried by the loose wheel, and a spring to return the draw-bar and loose wheel 35 to their normal position after being put in motion.
- 40 9. The combination, in a car-starter, of a power-shaft having a friction-wheel secured thereto, a loose wheel supported concentric with said shaft, a draw-bar, a connection between said draw-bar and loose wheel, a lock 45 to hold said draw-bar from being pulled out except when desired, a friction-band encircling the friction-wheel, a band-tightening device carried by the loose wheel, consisting of a frame pivoted to the loose wheel at its 50 inner end and having connections with the two ends of the friction-band and at differ-

ent distances from the pivot-connection of the frame, and a spring connected to the inner of said band-connections to release the friction-band and return the loose wheel to 60 its normal position.

10. The combination, in a car-starter, of a power-shaft having a friction-wheel secured thereto, a loose wheel supported concentric with said shaft, a draw-bar, a connection between 65 said draw-bar and loose wheel, a lock to hold said draw-bar from being pulled out except when desired, a friction-band encircling the friction-wheel, a band-tightening device carried by the loose wheel, consisting of the pivoted frame N, having a hinge-connection at n with the loose wheel and having rods O P connecting with the ends of the friction-band, and a spring acting upon the rod P to release the friction-band and return the 70 loose wheel to its original position.

11. The combination, in a car-starter, of a power-shaft having a friction-wheel secured thereto, a loose wheel supported concentric with said shaft, a draw-bar, a connection between 75 said draw-bar and loose wheel, a lock to hold said draw-bar from being pulled out except when desired, a friction-band encircling the friction-wheel, a band-tightening device carried by the loose wheel, consisting of the pivoted frame N, having a hinge-connection at n with the loose wheel and having an 80 extension, U, and having rods O P connecting with the ends of the friction-band, a spring acting upon the rod P to release the friction-band and return the loose wheel to its original position, and a stop, S, in the path of said extension U, to automatically release the friction-band when the loose wheel has made a 85 given portion of a revolution.

12. The combination of the axle of the car, a car - starter having a spirally - arranged groove or surface, a draw-bar and chain or rope therefor, a sprocket-wheel on the axle and the shaft of the car-starter and of different 90 diameters, and a chain connecting said sprocket-wheels and in which the smallest radius of the spiral groove is substantially equal to the radius of the smallest sprocket-wheel which is secured to the car-starter shaft.

In testimony of which invention I hereunto set my hand.

JOHN H. PALMER.
